UNITED STATES PATENT OFFICE.

HAROLD E. McCRAY, OF WATERLOO, IOWA, ASSIGNOR TO JOHN DEERE TRACTOR COMPANY, OF WATERLOO, IOWA, A CORPORATION OF IOWA.

INTERNAL-COMBUSTION ENGINE.

Original application filed February 15, 1923, Serial No. 619,081. Divided and this application filed April 27, 1925. Serial No. 26,152.

My invention relates to internal combustion engines of the horizontal type such as are commonly used for operating farm machinery. In such engines it is desirable that 5 the electric current required for ignition purposes be supplied by a magneto. The magneto must, of course, be driven by the engine, and my present invention has to do particularly with the arrangement of the 10 magneto and the mechanism for driving the same. It has for its object to provide for mounting the magneto so that it will be easily accessible, and for positively driving it from the crank shaft of the engine in 15 such manner that proper lubrication of such driving mechanism will always be assured, while the lubricant will be kept out of the magneto itself; also to provide a construction by which access may be had to the in- 20 terior of the crank case without disturbing the magneto setting. I accomplish this object as illustrated in the accompanying drawings and as hereinafter described. What I regard as new is set forth in the 25 claims.

In the drawings,—

Fig. 1 is a side elevation of my improved engine showing the magneto mounted on the crank case thereof, and illustrating in 30 dotted lines the driving train for the magneto;

Fig. 2 is a partial central longitudinal vertical section of the engine showing the interior of the crank case and the driving 35 train for the magneto located therein;

Fig. 3 is a partial vertical cross-sectional view showing the manner in which the magneto is mounted on the crank case, and some 40 of the driving connections thereof; and

Fig. 4 is a partial vertical cross-section on line 4—4 of Fig. 1.

Referring to the drawings, 5 indicates the base of my improved engine, which, in the illustrated construction, is in the form of a 45 hollow casting adapted to be bolted or otherwise suitably secured to a supporting plate 6, of wood or other suitable material, and to contain within it a fuel tank 7, which, as best shown in Fig. 3 occupies the greater 50 portion of the base 5. At its upper margins the fuel tank is provided with an outwardly-extending flange 8 which overlies an inwardly-projecting flange 9 at the upper margin of the base. A cover plate 10 fits

over the fuel tank 7, its marginal portions 55 resting on the flanges 8, as shown in Figs. 2, and upon the margins of this cover plate rest the marginal portions of a crank case 11. The crank case is securely bolted to the base 5 by bolts 12, as shown in Fig. 1. By 60 this construction the cover plate 10 serves as the top of the fuel tank and also as the bottom of the crank case. For the purpose of filling the fuel tank, the crank case 11 is provided with a passage 13, which is 65 formed in a boss 14 projecting from the lower portion of the crank case, and such passage is adapted to be closed by a plug 14^a or other suitable means. The passage 13 leads to a filling opening 15 in the cover 70 plate 10. A gasket 16 is placed between the crank case and cover plate 10 and around the opening 15 to prevent oil from leaking out of the crank case and into the fuel tank. For delivering the fuel from the fuel tank 75 I provide a pipe 17, which is connected with the inner end of said tank near the bottom thereof, and provided at its outer end with a plug 18 by the removal of which the tank 80 may be drained. Leading from the pipe 17 is a check valve 19, preferably of the ball type, made in the form of an elbow casting, and connected to said check valve by means of a coupling 20 is a supply pipe 21 leading to the fuel inlet of the engine cylinder. The pipe 17 and check valve 19 are 85 both located within the base 5, as shown in Fig. 2, and by this construction the check valve is protected and is not apt to be damaged in transporting the engine, as when the pipe 21 is uncoupled none of the parts connected with the fuel tank project beyond the base. It should be understood that the construction of the base, and the arrangement 90 of the fuel tank, as shown and described are not included in the subject-matter to which this application is particularly directed, but constitute that of a separate application filed of even date herewith. 95

The crank case constitutes also the main 100 engine frame, since cast integral with it is a combined cylinder block 22 and water hopper 23, as shown in Figs. 1 and 2. The engine cylinder 24 extends horizontally through the lower portion of the water hopper 23, but is separated therefrom laterally so that the water in the hopper surrounds 105 said cylinder. An opening is provided in

the bottom of the cylinder block 22 through which the water in the hopper may be drawn off, which opening is closed by a plug 25.

- 5 The crank case portion of the engine frame
is provided with a removable cover 26, the
outer end portion of which is secured thereto
by bolts 27 at opposite sides of the cover,
while its inner end portion is held in place
10 by an intermediate bolt 28 which extends
diagonally through a boss 29 in the cover
plate 26 into a boss 30 in that portion of the
engine frame which forms the inner wall of
the water hopper 23, as shown in Fig. 2.
15 The cover is made oil tight by providing
suitable gaskets between the margins of said
cover and the surface of the crank case
against which they bear. Access may
readily be had to the various part within the
20 crank case by removing the cover plate 26,
since when the cover is removed the interior
of the crank case is completely exposed.

30 of the crank case is completely dispensed. A crank shaft 31 having a crank portion 32 extends transversely of the crank case, 25 and the end portions of said crank shaft are mounted in suitable upper and lower bearings carried by the side walls of the crank case, the lower bearings being indicated by 33 and the upper bearings by 34, 30 (see Fig. 1). As shown in said figure, the side walls of the crank case adjacent to these bearings are cut away, and the lower bearings 33 are formed in depressed portions or recesses in said side walls. The upper bearings 35 35 are formed in removable blocks 35 which fit into said recesses and are held in place by bolts 36. The bearings 33, 34 are provided with the usual anti-friction linings 37, as shown in Fig. 1. The crank 40 shaft may readily be removed as occasion may require by removing the cover 26 and the blocks 35.

Referring now to Fig. 2, 38 indicates the piston of the engine, which operates in the cylinder 24, said piston being connected by a pitman 39 with the crank portion 32 of the crank shaft, which is preferably provided with two fly wheels 40, one at each side of the engine. One of said fly wheels is shown in Fig. 1.

Electric current for ignition purposes is furnished by a magneto 41 which is mounted on the crank case at one side thereof between the crank shaft and the water hopper, as best shown in Fig. 1, and below the position of the magneto is a chamber 42, best shown in Fig. 4, having a laterally disposed cover plate 43, which chamber contains certain controlling mechanism that need not be described as it has nothing to do with the subject-matter of this application. The cover plate 43 is removable so that access may be had to the parts contained in said chamber, and it is held in place by screws 44, as shown in Fig. 1.

The magneto 41 is driven from the crank shaft 31 by means of a train of gears located inside the crank case and subject to lubrication by the splash system, as hereininafter described, said train of gears comprising a pinion 45 mounted on the armature shaft 46 of the magneto and having a collar 47, preferably integral therewith, that projects through a substantially vertical slot 26^a in the crank case cover extending up from the lower edge thereof, as shown in Fig. 3; a gear 48 mounted on a transverse shaft 49 journaled in the side wall 11^a of the crank case, as shown in Fig. 4; and a pinion 50 mounted on the crank shaft 31, as shown in Fig. 2. The collar 47 serves to keep oil out of the magneto, and the slot 26^a in the cover 26 permits the cover to be removed without disturbing the magneto setting. To make a tight closure at this point the cover is provided with a separately removable plate 26^b and a gasket 26^c, that are secured to the outer face of the cover by one or more screws 26^d, and fit closely around the collar 47, as shown in Fig. 3. When the cover is to be removed said plate and gasket are first disconnected from it by withdrawing the screw or screws 26^d.

The lower portion of the crank case serves as an oil reservoir, oil being supplied thereto through an inlet 51, best shown in Fig. 1 and indicated by dotted lines in Fig. 2, said inlet preferably being in the form of a cylindrical boss projecting from the lower portion of the crank case at one side thereof, about midway of the length thereof, and normally the inlet is closed by a plug 52. Through this inlet the level of the oil may be observed, and it is located substantially at the center of the engine with respect to the fore and aft dimensions thereof, so that it will provide a safe gauge for ascertaining the level of the oil in the crank case, regardless of whether or not the engine has been set slightly out of level. Located within the crank case and secured to the bottom thereof is a pan 53, shown in Figs. 2 and 4, which has a hole or perforation 54 in it a short distance above the bottom thereof for admitting oil from the crank case to said pan, and at that side of said pan adjacent to the cylinder 24 it is provided with an upwardly-projecting curved deflector 55, the purpose of which will be herein-after explained. Arranged over and dipping into the pan 53 is a centrifugal governor 56 mounted on a transverse shaft 57 journaled in the side wall 11^a of the crank case, as shown in Fig. 4. Said governor comprises weighted levers 58 pivoted at 59 to diverging arms 60 which project from the inner end of the shaft 57, the levers 58 being provided with inwardly-projecting arms 61 which project toward the axis of the shaft 57. As the governor rotates the weighted

portions of the levers 58 tend to swing out, or away from the shaft 54, while the outer ends of the arms 61 tend to move inwardly in substantial alignment with the axis of 5 said shaft. This inward movement of the arms 61 is resisted by a spring 62 mounted on a rod 63 that extends axially through the shaft 57 and is provided with a head 64 at its inner end which underlies the inner ends 10 of the arms 61, as shown in Fig. 4. The spring 62 is fitted in a recess in the inner end portion of the shaft 57, and the inner end of said spring bears against an abutment formed at the inner end of said recess. By this construction the spring 62 tends to hold the governor in its normal position, but yields to permit the governor levers to swing out under centrifugal action. The governor is driven from the crank shaft 20 of the engine through the pinion 50 and gear 48, the latter of which connects with a pinion 65 mounted on the shaft 57. The same gears that drive the magneto also drive the governor 56, and this construction, 25 therefore, obviates the necessity of having two sets of gears for driving the two mechanisms. The governor is so arranged with reference to the pan 53 that when it is rotated by the operation of the engine and 30 the weighted levers 58 are thereby caused to swing outwardly, or away from the shaft 57, they then dip into the oil in said pan, and consequently act to distribute it throughout the crank case, thereby lubricating 35 the parts therein. The gears by which the armature of the magneto is rotated, as well as the armature shaft are therefore constantly lubricated, when the engine is in operation, but the oil is kept from passing 40 into the magneto itself by the collar 47. The plate 26^b and the gasket 26^c prevent the oil from passing out over the collar 47. Furthermore, when the cover is removed the driving gears of the magneto are completely 45 exposed so that access may easily be had to them.

Oil is supplied to the pan 53 from the crank case by the hole 54, which arrangement provides a simple and accurate means 50 for controlling the amount of oil thrown by the governor, which is limited to the amount that will pass through the hole 54. The pan serves to keep out sediment which may accumulate in the bottom of the crank case, and the sides of the pan also serve as deflectors to direct the oil throughout the interior of the crank case. The deflector 55 above referred to is provided to prevent an excessive amount of oil from being thrown 60 against the piston and into the cylinder, and I also prefer to provide an additional shield 66 in the form of a plate which extends transversely of the crank case adjacent to the inner end of the cylinder 24 and between 65 it and the pan 53, as shown in Fig. 2. Said

shield is secured at its upper margin to a flange 67 projecting downwardly from the cover plate 26, and is provided with a vertical slot wide enough for the passage of the pitman 39. The particular means shown 70 and described for distributing the lubricant is not herein claimed as it is included in the subject-matter of a separate application for patent, filed of even date herewith, and it should be understood that so far as my 75 present invention is concerned, any suitable means may be provided for applying the oil to the parts to be lubricated.

What I claim as my invention and desire to secure by Letters Patent, is— 80

1. In an internal combustion engine, the combination of a crank case, a removable cover therefor having a slot therein extending from one edge of said cover, a crank shaft disposed transversely of said crank case, a magneto exteriorly mounted on the crank case, and having its armature shaft extending through said slot gearing arranged inside the crank case for driving the armature shaft of said magneto, oil distributing means inside the crank case for lubricating said gearing, and means for preventing egress of oil through said slot. 85

2. In an internal combustion engine, the combination of a crank case, a removable cover therefor, a crank shaft disposed transversely of said crank case, a magneto mounted exteriorly on said crank case and having an armature shaft extending through said cover into the crank case, said cover being removable independently of said armature shaft, a pinion carried by said armature shaft, a collar around the armature shaft and extending through said cover, and means for driving said pinion from said crank shaft. 90

3. In an internal combustion engine, the combination of a crank case, a removable cover therefor, a crank shaft disposed transversely of said crank case, a magneto mounted exteriorly on said crank case and having an armature shaft extending through a slot in said cover into the crank case, said slot extending from one of the edges of said cover, a pinion carried by said armature shaft, a collar integral with said pinion and extending around the armature shaft through said slot, and means for driving said pinion from said crank shaft. 100

4. In an internal combustion engine, the combination of a crank case, a removable cover therefor, a crank shaft disposed transversely in said crank case, a magneto mounted exteriorly on said crank case at one side thereof and having an armature shaft extending through a slot in said cover, a pinion carried by said armature shaft and having a collar extending through said slot, a detachable plate carried by the cover outside of said slot and fitting around said col- 115 120 125 130

lar, and means for driving said pinion from said crank shaft.

5. In an internal combustion engine, the combination of a crank case, a removable cover therefor, a crank shaft disposed transversely in said crank case, a magneto mounted exteriorly on said crank case at one side thereof and having an armature shaft extending through a slot in said cover, a pinion carried by said armature shaft and having a collar extending through said slot, a detachable plate carried by the collar outside of said slot, a gasket between the plate and the cover fitting around said collar, and 10 means for driving said pinion from said crank shaft.

6. In an internal combustion engine, the combination of a crank case comprising two separable sections, a crank shaft in said 20 crank case, a magneto, a shaft extending through said crank case and driven at its inner end from said crank shaft and operatively connected at its outer end to said magneto, said shaft passing through a slot 25 in one of said crank case sections, which slot extends to one of the edges of said latter section whereby said section can be removed without interrupting the driving relation to said magneto, and means for protecting the magneto against the discharge 30 of lubricant through said slot.

7. In an internal combustion engine, the combination of a crank case comprising two

separable sections, a magneto mounted exteriorly of said crank case, a driving member passing through said crank case and adapted to be driven at its inner end from within said crank case and adapted to impart operative motion to said magneto, said driving member passing through a slot in 35 one of said crank case sections, which slot extends to one of the edges of said latter section whereby said section can be removed without interrupting the driving relation to said magneto, and a detachable closure member 40 for covering said slot against the egress of lubricant.

8. In an internal combustion engine, the combination of a crank case, a removable cover therefor, a crank shaft journaled in 50 said crank case, a magneto supported exteriorly of said crank case, a rotary member passing through said crank case, means within said crank case for driving said rotary member from said crank shaft, means 55 operatively connecting said rotary member with said magneto, said rotary member being disposed within a slot in said removable cover, said slot extending to the lower edge 60 of said cover and permitting removal of said cover independently of said rotary member, and a closure plate detachably connected to said cover for closing said slot around said rotary member.

HAROLD E. McCRAY.
